UNITED STATES PATENT OFFICE

JOHN H. CRAIG, OF OIL CITY, PENNSYLVANIA

TYPEWRITER COPYHOLDER

Application filed May 17, 1930. Serial No. 453,303.

This invention relates to improvements in paper and book supports and pertains particularly to an improved copy stand designed particularly for the use of typists.

5 The primary object of the present invention is to provide a copy stand which is foldable and which may be readily adjusted for height and for width to support sheets or books at the proper angle for copying.

10 Another object of the invention is to provide a copy stand which in addition to being adjustable as a whole to increase or decrease its width, has as a part thereof book or sheet supporting elements which may be adjusted 15 relative to one another transversely of the stand structure.

A still further object of the invention is to provide a novel type of copy stand which may be applied to a disappearing type of 20 typewriter so that the stand may be shifted with the typewriter when the portion of the typewriter desk structure upon which the latter is mounted is shifted to close the desk and to cover the typewriter.

25 Still another object of the invention is to provide a copy stand having several minor novel features of construction whereby the stand is made more serviceable and better adapted to perform the several functions for 30 which it is designed.

The invention will be best understood from a consideration of the following detailed description taken in connection with the accompanying drawings forming part of this 35 specification, with the understanding, however, that the invention is not confined to any strict conformity with the showing of the drawings but may be changed or modified so long as such changes or modifications mark 40 no material departure from the salient features of the invention as expressed in the appended claims.

In the drawings:

45 Figure 1 is a view in front elevation of the stand embodying the present invention.

Figure 2 is a view in top plan of the same.

Figure 3 is a sectional view taken on the line 3—3 of Figure 1.

50 Figure 4 is an enlarged detailed section of the connection between a leg and the stand.

Figure 5 is a view in plan of a portion of a typewriter desk showing a method of securing the stand thereto.

Referring more particularly to the drawings wherein like numerals of reference indicate corresponding parts throughout the several views, it will be seen that the copy stand embodying the present invention comprises two main portions, that is the base 1 and the back 2 each of which is in the form 60 of a rectangular frame.

The base 1 consists of the flat side bars 3 normally disposed in parallel relation and each having at its forward end and pivotally attached thereto as at 4 by a rivet or other suitable means a longitudinally slotted link 5, the two links 5 being adapted to be swung to a position where their free ends may be brought into overlapping relation to receive a removable securing element 6 thus 70 converting the links 5 into a front bar for the base.

The back 2 is made up of the upright side bars 7 each of which is divided into two portions, each of which portions has a longitudinally extending slot 8 therein, the overlapping end of one of the portions carrying a pin 9 which slidably engages in the slot of the adjacent portion while the end of the said adjacent portion carries a thumb screw 80 10 which passes through the slot of the other portion and when manipulated serves to tighten the connection between the two portions 7 so that they will be held in any desired adjusted position. The lower end of 85 each bar 7 has hinge connection as at 11 with the rear end of the adjacent base bar 3, this connection being such that the back may be swung forwardly and face down onto the base when the stand is folded.

90 Connecting the lower ends of the bars 7 is a transverse two part bar 12 each of the parts being indicated by the numeral 12a and each having formed therethrough a longitudinally extending slot 13. The adjacent ends of the 95 portions 12a of the bar 12 are arranged in overlapping relation and are slidably connected by a thumb nut and screw 15 the screw passing through the slots of the bars. At the upper ends of the bars 7 a cross connecting 100

top bar 16 is positioned, this top bar also being in two portions and constructed in exactly the same manner as the bottom bar 12, the ends of the top bar 16 being riveted as at 5 17 to the adjacent side bars 7.

Intermediate the ends of the side bars 7 there is positioned an intermediate transverse bar which is indicated generally by the numeral 18. This bar 18 is in two portions, each 10 of which is slotted, and these are in end overlapping relation and have a thumb screw 18' extending therethrough to retain them together. At its outer ends the transverse bar 18 is traversed by the thumb screws 10 15 which connect the two portions of the side bars 7 together. A pair of legs 19 is provided for the support of the back 2 each of which legs is made in two portions, the overlapping ends of which are held in sliding engagement by a thumb screw 20 which is carried by one portion and works in a longitudinal slot in the other portion, the said other portion carrying a pin which works in a longitudinal slot formed in the portion 20 25 which carries the thumb screw. The construction of the legs in this respect is the same as the side bars and the cross connecting bars of the back.

The outer end of one portion of each leg 30 19 is bent to extend at an angle therefrom as indicated at 21, this angled portion of each leg constituting the top of the leg and having in the face thereof a headed stud 22 which has had opposite sides thereof cut 35 away as indicated at 23. These legs are connected to the back by positioning them longitudinally of the bar 16 so as to permit the insertion of the head of the stud 22 into the slot of one of the portions of the bar 16 after 40 which the leg is turned to a position where it extends transversely of the attached bar. With the angled portion 21 of each leg positioned against the attached bar 16 the leg will extend therefrom at such an angle that 45 the back 2 will be maintained in a rearwardly inclined position.

Arranged to extend across the forward faces of the bars 16 and 18 is a pair of supporting bars 24 each of which has its upper 50 end turned to form a hook 25 which engages over the top bar 16. Each of these supporting bars 24 is longitudinally slotted as indicated at 24a to receive the shank of a support hook 26. The shanks of these hooks 26 55 are threaded as shown and carry a pair of nuts 27 which are disposed upon opposite faces of the bars 24 through which the shanks pass. For all ordinary occasions the shanks may also be extended through the slots 60 formed in the portions of the intermediate transverse bar 18 so that any tendency on the part of the supporting bars 24 to oscillate will be prevented.

Each portion of the top bar 16 has adjustably attached thereto the turned end 28 of

a spring arm 29, the connection between the portion 28 of each arm and the adjacent portion of the bar 16 being by means of a screw and thumb nut 30 by means of which the spring arm may be secured in any desired 70 adjusted position on the bar 16.

A leaf holder extends across the face of the back 2 at the upper portion thereof and comprises a pair of hooks each of which is indicated by the numeral 31 which engages over the outer edge of a side bar 7, and a connecting cord 32 between the hooks having interposed therein one or more springs 33. It will be seen that the springs 33 tend to maintain the cord 32 taut toward the front 80 of the rest back so that when a book or leaf is rested upon the two hooks 26 this cord may be placed over the same and will thus maintain the leaves of the book or the sheet 85 in the proper position.

In Figure 5 I have illustrated the manner in which the copy or book stand may be attached to the shiftable top portion of a typewriter desk to which a typewriter is ordinarily secured. This shiftable portion of a typewriter desk is indicated generally by the numeral 34 and as is well known is usually mounted upon pivot arms so that when it is shifted by the opening or closing of the typewriter desk the typewriter carried thereby will be brought into view or covered as desired. As is also well known these shiftable portions of typewriter desks carry a sliding panel 35 upon which a typewriter is mounted and metal cleats 36 are usually attached to the portion 34 and overlying the panel 35 to maintain the latter in sliding engagement with the portion 34. 90

By removing the thumb screw 6 which connects the two portions 5, 5 making up the front bar of the stand base, and swinging these portions out to a position where they are in alignment with the sides 3, the sides 3 and the portions of the front cross bar may be slipped beneath the guides 36 after the holding screws therefor have been loosened and upon retightening these screws after slipping the elements 3 and 5 therebeneath it will be readily seen that these parts of the stand base will be firmly secured in place so that the copy stand may be shifted with the typewriter which is supported upon the body 100 110 115 34, after the back 2 has been folded forwardly against the typewriter.

From the foregoing description it will be readily seen that the present copy stand structure is such that it may be readily folded to be put away or it may be readily adjusted both for height and for width according to the size of the book or sheet which is to be supported thereby. When the book or sheet is in position upon the stand the cord 32 may be extended across the face thereof and in order to further maintain the leaves of the book or the sheet in the proper position the spring 120 125 130

arms 29 may be swung around to a position where they are substantially parallel with the sides of the stand back and overlying the sheet or body upon the stand.

5 Having thus described my invention, what I claim is:

1. A typewriter copy stand, comprising a base in the form of a rectangular frame having a pair of side bars and a two part transverse front bar connecting the side bars, said two part front bar being adjustable for length, a back frame comprising a pair of side bars and upper and lower cross bars connecting the side bars, said side bars and said cross bars each being longitudinally adjustable, supporting elements attached to the back for maintaining it in upright position, a hinge connection between the lower portion of the back and each of the side bars of the base, a pair of bars detachably carried by the back and extending downwardly from the top thereof, and a copy sheet holder carried by each of said last mentioned bars and adjustable longitudinally thereon.

25 2. A typewriter copy sheet holder, comprising a base of rectangular design and consisting of a pair of side bars and a transverse longitudinally adjustable front bar connecting the side bars, a back frame of substantially rectangular design consisting of a pair of side bars each being longitudinally adjustable, and an upper, an intermediate and a lower cross bar connecting the last mentioned side bars and each being longitudinally adjustable, a hinge connecting one end of each side bar of the back with a side bar of the base, a removable prop leg carried by the back, a pair of support bars carried by the upper bar of the back and extending 46 down over the intermediate bar, and a copy sheet supporting element carried by each support bar and adjustable longitudinally thereof.

3. A typewriter copy holder, comprising a base, an upright back hingedly attached to said base, means carried by the back for supporting a copy sheet thereon, said base comprising a rectangular frame having a front bar divided intermediate its ends, removable means normally connecting the portions of said front bar, and pivotal connections between the portions of said front bar and adjacent portions of the base whereby the front bar portions may be rotated to longitudinal alignment with the attached base portions to facilitate securing the stand to a typewriter support.

4. A typewriter copy stand, comprising a base having flat spaced side bars, a front connecting cross bar between said side bars, said front bar being longitudinally adjustable, a back comprising upright side bars each pivotally attached to a side bar of the base and upper, intermediate and lower cross bars, 65 said back side bars and said upper, inter-

mediate and lower cross bars being longitudinally adjustable, said upper bar having longitudinal slots therein, supporting legs each having a headed stud at one end adapted to be engaged in a slot of the top bar and each of said legs being longitudinally adjustable, support bars each having a hook at one end adapted to engage over said top bar and each resting against said intermediate bar, and supporting hooks carried by 75 said support bars and each longitudinally adjustable thereon.

5. A typewriter copy stand, comprising a base having flat spaced side bars, a front connecting cross bar between said side bars, said front bar being longitudinally adjustable, a back comprising upright side bars each pivotally attached to a side bar of the base and upper, intermediate and lower cross bars, said back side bars and said upper, intermediate and lower cross bars being longitudinally adjustable, said upper bar having longitudinal slots therein, supporting legs each having a headed stud at one end adapted to be engaged in a slot of the top bar and 80 each of said legs being longitudinally adjustable, support bars each having a hook at one end adapted to engage over said top bar and each resting against said intermediate bar, supporting hooks carried by 85 said support bars and each longitudinally adjustable thereon, resilient means carried by and extending transversely of the back for maintaining a sheet in position thereagainst, and spring members pivotally attached to the upper bar of the back adapted to overlie a sheet member to maintain the same in position against the back in cooperation with said resilient means.

In testimony whereof I hereunto affix my 105 signature.

JOHN H. CRAIG.
